(57) **CLAIM**

The ornamental design for an ottoman for a commercial aircraft passenger cabin, as shown and described.

DESCRIPTION

FIG. 1 is a front, left perspective view of an ottoman for a commercial aircraft passenger cabin according to my design;

FIG. 2 is a top plan view thereof;

FIG. 3 is a left side elevation view thereof;

FIG. 4 is a right side elevation view thereof;

FIG. 5 is a rear elevation view thereof;

FIG. 6 is a front elevation view thereof;

FIG. 7 is a rear, left perspective view of the ottoman of FIG. 1 shown with a commercial aircraft passenger cabin seat and partition;

FIG. 8 is a top plan view of the ottoman, seat and partition shown in FIG. 7; and,

FIG. 9 is a top plan view of the ottoman of FIG. 1 shown in a commercial aircraft passenger cabin. Another embodiment of the ottoman for a commercial aircraft passenger cabin is a mirror image of the design shown in FIGS. 1-9.

No bottom plan view is included as no features of the claimed design are visible therein.

Throughout the Figures, the broken lines and non-shaded areas showing environment or structure are for illustrative purposes only and form no part of the claimed design. Dash-dot broken lines represent the boundary between claimed and unclaimed areas and form no part of the claimed design. Dotted lines represent elements of the environment and form no part of the claimed design.
